DESIGN FOR A HOUSE COAT OR SIMILAR ARTICLE

Ruth F. Campbell, New York, N. Y.

Application February 25, 1937, Serial No. 67,847

Term of patent 3½ years

To whom it may concern:

Be it known that I, Ruth F. Campbell, a citizen of the United States, residing at New York, in the city, county, and State of New York, have invented a new, original, and ornamental Design for a House Coat or Similar Article, of which the following is a specification, reference being had to the accompanying drawing, forming part thereof, wherein—

Fig. 2 is a perspective view of the house coat of my new design showing the garment partly closed.

My design comprises a house coat, as shown, said coat having fitted lines extending from the shoulders to a point below the hipline, a flared skirt portion, a slide fastener located on the side of the coat and extending from the lower portion of the skirt to the shoulder seam, and a convertible neckline, all as shown.

The back of the house coat is conventional.

I claim:

The ornamental design for a house coat or similar article substantially as shown and described.

RUTH F. CAMPBELL.
